SHEET APPARATUS

Maurt T. McDearmid, Sand Springs, Okla.

Application June 5, 1942, Serial No. 445,931

4 Claims. (Cl. 271—63)

This invention relates to an improved apparatus for facilitating the tearing of sheeting into strips of the desired length, and for storing said strips preparatory to hemming the ends thereof in the manufacture of bed sheets.

The primary object of the present invention is to provide an apparatus of the above kind by means of which the strips of sheeting may be produced with comparative ease and rapidity with the use of a minimum amount of manual labor.

A more specific object of the present invention is to provide an apparatus of the above kind embodying simple and efficient means for folding the strips of sheeting and storing the same in quantities as they are produced.

Other objects and features of the present invention will become apparent from the following description when considered in connection with the accompanying drawings, and the invention consists in the novel form, combination and arrangement of parts hereinafter more fully described, shown in said accompanying drawings and claimed.

In the drawings:

Figure 1 is a side elevational view of a sheet apparatus embodying the present invention.

Figure 2 is a top plan view thereof.

Figure 3 is an enlarged view showing an end portion of the apparatus in vertical longitudinal section so as to reveal certain details of construction.

Figure 4 is a transverse section taken on line 4—4 of Figure 1.

Figure 5 is a transverse section taken on line 5—5 of Figure 1.

Figure 6 is a transverse section taken on line 6—6 of Figure 1; and

Figure 7 is a perspective view showing one of the bars over which the sheet strips are folded and stored in quantities.

Referring in detail to the drawings, the present apparatus comprises an elevated table 5 having an elevated platform 6 constructed along one side of and below the same, steps 7 being provided at one end of the platform 6 to facilitate ascension of the operator to the platform 6. Suitably arranged upon the floor beneath the table 5 is a mounting 8 for receiving the supply roll 9 of sheeting. The platform 6 extends inwardly under the table 5, and a guide roller 10 is journaled at the forward end of this portion of the platform. Arranged beneath the table 5 and above the platform 6 are a series of shelves 11 having guide rollers 12 journaled at opposite ends

thereof, the arrangement being such that the sheeting is extended from the roll 9 forwardly and upwardly around the guide roller 10 to the guide roller 12 at the forward end of the uppermost shelf 11. The sheeting is then extended back and forth around the rollers 12 and above the shelves 11, and finally rearwardly above the platform 6 to a guide roller 12 mounted above the rear end of a rearward extension 13 of the platform 6 which extends rearwardly beyond the table 5 as shown clearly in Figure 3. Mounted upon the extension 13 is a frame 14 having coacting feed rollers 15 journaled at the top thereof, one of which is power driven by means of a motor 16 and suitable belt gearing 17. The motor 16 is mounted upon a suitable base 18 fixed upon the platform extension 13 as is also clearly shown in Figure 3. After passing around the guide roller 12 rearwardly of the frame 14, the sheeting extends upwardly and then forwardly between the feed rollers 15. In passing from the roll 9 to the feed rollers 15 in this way, the sheeting is fed forwardly toward the rear end of table 5 in a smooth or unwrinkled condition. Arranged between the feed rollers 15 and the rear end of table 5 is a trough 19 in which the sheeting may gather as at 20 to provide a reserve supply from which the sheeting may be drawn for marking and tearing into strips of desired lengths while on the table 5 and by means of an operator standing on the platform 6 beside and near the forward end of said table 5. To facilitate marking and tearing of the sheeting into strips of the desired length, a suitable marking device 21 is mounted upon the table 5 near its rear end, and a conventional knife 22 is mounted near the forward end of table 5 along the edge thereof for slitting the edge of the sheeting preparatory to manual tearing of the same by the operator. The knife 22 is adjustably mounted as at 23 for adjustment longitudinally of the table and relative to the marker 21 so that the length of the sheet strips may be varied according to the length of sheets it is desired to produce.

Hinged to the forward end of table 5 is a leaf 24 normally adapted to gravitate to a lowered position as shown by dotted lines in Figure 3 and adapted to be manually raised and held into a horizontal position coextensive with the table 5 as shown in Figure 3. The elevation of leaf 24 is adapted to be effected by the operator standing on the platform 6, by suitable means such as a foot lever 25 operatively connected with leaf 24 at one side of the latter by means of a cable 26 extending along guide rollers 27 and 28 and

connecting one end of lever 25 with the leaf 24 at one side of the latter as clearly shown in Figure 5. Arranged forwardly and slightly below the level of table 5, as well as extending forwardly from a point below the forward end of leaf 24 are a pair of spaced endless conveyor belts 29 driven by means of a motor 30 through suitable belt gearing 31. Extending forwardly and downwardly from the conveyor belts 29 at a slight inclination are supporting rails 32 coextensive with the conveyor belts 29 and carried by suitable framework 33; the motor 30 is mounted upon a base 34 above the rails 32 and forwardly of the conveyor belts 29.

In use, a sheet strip supporting bar 35 is placed upon the conveyor belts 29 as shown in Figure 3 directly in front of the leaf 24. The motor 16 is then placed into operation so as to feed the sheeting into the trough 19 where it accumulates in folds as illustrated. From this trough, the sheeting is drawn by the operator over the surface of table 5, the end of the sheeting being extended to the knife 22 and a mark being made upon an edge of the sheeting by the marker 21 at the desired distance from said end of the sheeting. The sheeting is then drawn forwardly until the part of the sheeting containing said mark is brought at the cutter 22 where the sheeting is slit transversely at one edge. The sheeting is then torn transversely at this slit so as to produce a strip of sheeting the desired length. Additional strips are produced by repeating this operation, the lengths of the strips depending upon the position at which the knife 22 is adjusted longitudinally of the table relative to the marker 21. As the strips are produced, they are drawn forwardly over the leaf 24 and draped forwardly over the supporting bar 35. When the desired number of strips have been placed upon the bar 35, the conveyor belts 29 are placed into operation so as to feed this bar and its batch of strips forwardly onto the rails 32. However, before placing the conveyor belts 29 into operation, each strip of sheeting is folded over the supporting bar 35 by dropping the leaf 24 to the dotted line position of Figure 3 through release of foot lever 25. Thus, the strips will be stored in quantity on each supporting bar 35 in centrally folded condition as illustrated in Figure 3. The batches of sheet strips stored upon bars 35 may be manually shifted forwardly on rails 32 so that the latter will be able to contain a large number of these batches which may be selectively removed from time to time and taken to sewing machines for stitching hems on the ends of the strips and producing the complete sheets.

The table and shelves are preferably marked, beginning where cloth enters at roller 12, at intervals of 9 inches. The operator, from his readings of said markings, is enabled to tear sheets of varying lengths. In other words, there are 1188 inches of cloth in the apparatus and if no defect appears in the cloth the operator can tear eleven 108 inch sheets from the cloth in the apparatus. If a defect appears in any place in the cloth in said apparatus, the operator, by the quick calculation which can be made from the markings on the table, can determine the length for tearing the greatest number of sheets with the least possible waste. For example, where a defect appears the operator may tear ten 108 inch sheets and one 99 inch sheet, or, may tear ten 99 inch sheets and two 90 inch sheets, and in so doing the defect is torn out with less loss than would be sustained in tearing all sheets of the

same length. If the table is correctly read, the maximum amount of waste will be 8 inches. In actual operation, let us assume a defect appears in the cloth, on the shelf and at a point thereon where the reading is 945 inches, the operator may tear six 108 inch sheets and three 99 inch sheets, or, five 99 inch sheets and five 90 inch sheets from this point or reading, and thereby tear out the defect with a minimum loss of cloth. At no time will this loss exceed 8 inches.

From the foregoing description, it will be seen that I have provided a very simple, efficient and highly useful apparatus of the character described which will enable the production of sheet forming strips in considerable quantity and in an expeditious manner with the employment of a minimum amount of manual labor.

Minor changes in the detail of construction illustrated and described are contemplated such as fall within the spirit and scope of the invention as claimed.

What I claim as new is:

1. A sheet apparatus of the character described comprising an elevated table having an elevated platform arranged along one side of and below the same, means for feeding sheeting to one end of said table, a strip folding leaf hinged for vertical swinging movement to and at the other end of said table, means to elevate the leaf to a horizontal position coextensive with said table, conveying means extending forwardly from said leaf and adapted to contain a sheet strip supporting bar transversely of the table in a position forwardly of the latter and the leaf, whereby strips of sheeting torn upon the table may be fed forwardly over the supporting bar and folded over the latter by dropping said leaf.

2. A sheet apparatus of the character described comprising an elevated table having an elevated platform arranged along one side of and below the same, means for feeding sheeting to one end of said table, a strip folding leaf hinged for vertical swinging movement to and at the other end of said table, means to elevate the leaf to a horizontal position coextensive with said table, conveying means extending forwardly from said leaf and adapted to contain a sheet strip supporting bar transversely of the table in a position forwardly of the latter and the leaf, whereby strips of sheeting torn upon the table may be fed forwardly over the supporting bar and folded over the latter by dropping said leaf, the feeding means for the sheeting including power driven feed rollers disposed rearwardly of and in spaced relation to the table, and a trough interposed between the table and said feed rollers wherein the sheet may accumulate and fold to afford a reserve supply of sheeting from which the latter may be drawn onto the table preparatory to tearing the same into strips of desired length.

3. A sheet apparatus of the character described comprising an elevated table having an elevated platform arranged along one side of and below the same, means for feeding sheeting to one end of said table, a strip folding leaf hinged for vertical swinging movement to and at the other end of said table, means to elevate the leaf to a horizontal position coextensive with said table, conveying means extending forwardly from said leaf and adapted to contain a sheet strip supporting bar transversely of the table in a position forwardly of the latter and the leaf, whereby strips of sheeting torn upon the table may be fed forwardly over the supporting bar and folded over the latter by dropping said leaf, the feeding

means for the sheeting including power driven feed rollers disposed rearwardly of and in spaced relation to the table, and a trough interposed between the table and said feed rollers wherein the sheet may accumulate and fold to afford a reserve supply of sheeting from which the latter may be drawn onto the table preparatory to tearing the same into strips of desired length, a marker for the sheeting provided on the table near its rear end portion, and a sheeting slitting knife mounted along an edge of the table near its forward end, said knife being adjustable longitudinally of the table relative to the marker.

4. A sheet apparatus of the character described comprising an elevated table having an elevated platform arranged along one side of and below the same, means for feeding sheeting to one end of said table, a strip folding leaf hinged for vertical swinging movement to and at the other end of said table, means to elevate the leaf to a horizontal position coextensive with said table, conveying means extending forwardly from

said leaf and adapted to contain a sheet strip supporting bar transversely of the table in a position forwardly of the latter and the leaf, whereby strips of sheeting torn upon the table may be fed forwardly over the supporting bar and folded over the latter by dropping said leaf, the feeding means for the sheeting including power driven feed rollers disposed rearwardly of and in spaced relation to the table, and a trough interposed between the table and said rollers wherein the sheet may accumulate and fold to afford a reserve supply of sheeting from which the latter may be drawn onto the table preparatory to tearing the same into strips of desired length, inclined supporting rails arranged to receive the sheet strip supporting bars after being shifted forwardly by the conveying means, and upon which a number of the sheet strip supporting bars with batches of strips thereon may be stored preparatory to hemming the ends of the strips.
